UNITED STATES PATENT OFFICE.

CLIFFORD C. BRADBURY, OF CHICAGO, ILLINOIS, ASSIGNOR TO ARTHUR L. PAYTON,
OF CHICAGO, ILLINOIS.

AUTOMATIC FUEL-FEED SYSTEM FOR CARBURETERS.

1,364,479.

Specification of Letters Patent.

Patented Jan. 4, 1921.

Application filed April 12, 1916. Serial No. 90,634.

To all whom it may concern:

Be it known that I, CLIFFORD C. BRADBURY, a citizen of the United States, residing at Chicago, in the county of Cook and 5 State of Illinois, have invented certain new and useful Improvements in Automatic Fuel-Feed Systems for Carbureters, of which the following is a full, clear, concise, and exact description, reference being had to the 10 accompanying drawings, forming a part of this specification.

My invention relates to automatic fuel feed systems for carbureters. The invention has for its object mechanism by which 15 the fuel may be lifted from a main supply tank at a lower level than the carbureter to a secondary supply tank at or above the level of the carbureter, such, for example, as the float chamber of the carbureter itself, the de- 20 pression in pressure produced by the suction of the engine being used to cause the flow of gasoline from the lower to the higher level.

The commercial carbureters for automo- 25 biles as constructed at the present time are so designed and proportioned that at the lowest engine speeds, that is, at what is known as idling speed, a difference in pressure between the end of the spray nozzle in- 30 side the atomizing chamber and the surface of the gasoline in the float chamber of the equivalent to $1\frac{1}{2}$ to 2 inches of gasoline is maintained. This difference in pressure is ordinarily brought about by restricting the 35 atmospheric entrance into the atomizing chamber of the carbureter. It is the object of my invention to so arrange my carbureter that the same difference in pressure between the atomizing chamber and the surface of 40 the gasoline in the float chamber may be maintained as is maintained with the ordinary gravity feed carbureter, but at the same time to bring about a general depression in pressure both inside of the atomizing 45 chamber and within the float chamber, so that the general depression may be used for lifting the gasoline from the main supply tank to the carbureter. In order, further- 50 more, that this general depression may be very slight but may still be sufficient to lift gasoline through a distance which may under some circumstances amount to 30 or 40 inches, I provide an automatic mixing device within the main gasoline reservoir, by 55 means of which air is mixed with the gaso-

lene, so that the specific gravity of the gasoline is automatically reduced and automatically proportioned to the available suction. This can only be accomplished where the tube leading from the main gasoline supply 60 to the secondary gasoline supply is sufficiently small in diameter that the capillary attraction or surface tension of the gasoline will cause the bubbles of air to extend entirely across the tube and thus at least for a 65 short period of time serve as effectual dams to prevent the gasoline which is entrapped between the bubbles of air from returning past the air to the main supply tank.

This automatic arrangement is such that 70 even though the suction is sufficient only for lifting gasoline a distance of two or three inches when the gasoline is not intermingled with air, it will nevertheless be lifted any distance, even 40 or 50 inches, in sufficient 75 quantities to supply all the needs of the ordinary carbureter when it is mixed with air by the automatic mixing arrangement of my invention.

One specific structure, by means of which 80 these results are brought about, is fully described in the following detailed description and is illustrated in the accompanying drawings, in which—

Figure 1 illustrates a side elevational view 85 of an automobile provided with the system of my invention, some of the parts of the automobile being broken away to more clearly illustrate the construction of the several parts of the system.

Fig. 2 is an enlarged detailed view of the air intake openings in the fuel conduit and the means for regulating the air to the openings from the outside of the reservoir.

Fig. 3 is a vertical cross sectional view of 95 the carbureter illustrated in Fig. 1. This view is taken along the line 3—3 of Fig. 1, looking in the direction indicated by the arrows.

Similar characters of reference refer to 100 similar parts throughout the several views.

The system of my invention is intended primarily to be used on automobiles and is thus illustrated in Fig. 1, wherein 4 illustrates the internal combustion engine pro- 105 vided with the intake manifold 5. The carbureter 6 is arranged to communicate with the intake manifold in the usual manner and may receive air through a conduit 7, terminating at a heater for heating the in- 110

coming air before it reaches the carbureter. The carbureter is also provided with the auxiliary air intake mechanism indicated generally at 8 and the usual float chamber 9 communicating with the fuel supply conduit 10. The fuel chamber may, if desired, be provided with the float 11 to discontinue communication between the fuel chamber and the supply conduit when the fuel reaches a certain level within the chamber. Located below the level of the fuel chamber of the carbureter is a supply reservoir 12 containing a vent opening 13. The conduit 10 extends downwardly from the carbureter through the top of the supply reservoir 12 and into the fuel contained therein. That portion of the conduit 10 which is disposed within the fuel reservoir is provided with a plurality of restricted air intake openings 14—14 which are spaced one above the other throughout such portion of the conduit. The upper one of the apertures 14 is positioned to at all times lie above the level of the fuel contained in the reservoir. Carried by the conduit 10 and extending around the apertures 14 is an outer tube 15 open at the bottom to admit the fuel around the conduit 10, as illustrated in Fig. 2. The upper end of the outer tube 15 is provided with a single air intake opening 16 which is regulated by means of a screw 17 extending through the top of the reservoir. The holes 14—14 in that portion of the conduit 10 disposed within the fuel reservoir are of a size such that the cross-sectional area of their openings combined will equal substantially the cross-sectional area of the adjusted opening 16 in the tube 15.

As illustrated in Fig. 3 the fuel chamber 40 of the carbureter communicates through the nozzle 16' with the atomizing chamber 17'. This atomizing chamber communicates with the chamber 18 formed by the elbow 19 through the restricted port 20. The chamber 18 and port 20 constitute the primary intake of the carbureter which is connected with the conduit 7 above referred to. The elbow 19 carries a stationary rod 21 upon which is slidably mounted a valve 22 seated by means of a spring 23 against pressure within the conduit 7. The chamber 18 communicates with the fuel chamber 9 above the level of the fuel contained therein through the conduit 24. An air intake port 55 is provided at 25 controlled by the valve 26 normally seating against atmospheric pressure for providing communication between the fuel chamber 9 and the atmosphere when a certain predetermined reduction of pressure is produced within the fuel chamber.

As a vacuum or reduction of pressure is produced within the atomizing chamber 17' the pressure within the chamber 18 is also reduced, but on account of the restricted port 20 the pressure within the chamber 18

is always slightly greater than the pressure within the atomizing chamber 17'. Since the fuel chamber 9 communicates with the chamber 18 the pressure within the fuel chamber will be substantially that of the chamber 18 which, as has been pointed out, is greater than the pressure within the atomizing chamber. This difference in pressure is necessary in order to feed the fuel through the nozzle 16'. The reduction of pressure produced within the chamber 18 is substantially constant due to the restricting valve 22, but in order to positively prevent too great a reduction of pressure in the fuel chamber the automatic valve 26 is provided to admit air into the fuel chamber when the chamber is subjected to a pressure less than a predetermined amount.

As the level of the fuel in the fuel chamber is lowered the float valve 11 opens and permits communication between the fuel chamber and the conduit 10. As soon as such communication is provided the pressure within the conduit is lowered and fuel caused to flow upwardly from the supply reservoir into the conduit. If the reduction of pressure in the fuel chamber is sufficient to raise the fuel only a few inches, let us say two inches, the elevated fuel of course does not reach the carbureter but stands in the conduit two inches above the level of the fuel in the reservoir. Since, however, the upper one of the air intake apertures 14 communicates with the outside atmosphere a bubble of air is taken in through this aperture under the column of elevated fuel. The intermingling of this air bubble with the fuel serves to reduce the specific gravity of the fuel in the conduit and allows the fuel to be elevated with but a slight reduction of pressure up to the fuel chamber of the carbureter. As the level of the fuel in the reservoir is lowered it is, of course, necessary to elevate the fuel a greater distance which necessitates the reducing of the specific gravity of the fuel in the conduit to a greater extent than is necessary when the supply reservoir is full. When, therefore, the fuel level is lowered more of the apertures 14 are uncovered, each permitting the intake of air into the column of elevated fuel. It is to be noted that the air intake apertures 14 are arranged so that no matter at what height the fuel in the supply reservoir stands there will be at all times one air intake opening which is positioned between the level of the fuel in the reservoir and the level of the elevated fuel in the conduit so that a bubble of air is formed underneath the column.

Some difficulty has been encountered in the past in using the so-called "vacuum" system in high altitudes for the reason that the fuel in the supply reservoir is not subjected to enough pressure to elevate it to

the carbureter. Difficulty has also been encountered in this system when climbing hills, since the carbureter is thus on account of the incline positioned a greater distance 5 above the supply reservoir. By the system of my invention these difficulties are overcome and the fuel can be elevated with but a slight reduction of pressure to a considerable height.

10 Having thus described my invention, what I claim as new and desire to secure by Letters Patent of the United States is:

1. The combination of an internal combustion engine, a carbureter connected with 15 the intake manifold thereof and having its fuel chamber communicating with the intake manifold, whereby upon operation of the engine the fuel chamber is subjected to pressure below that of atmospheric pressure, 20 a fuel supply reservoir located below the fuel chamber of the carbureter and having the fuel contained therein subjected to atmospheric pressure, and a fuel conduit communicating with the interior of the fuel 25 chamber and extending downwardly through the top of the supply reservoir into the fuel contained therein, that portion of the conduit lying between the top of the reservoir and the fuel contained therein being 30 provided with an air intake opening.

2. The combination of an internal combustion engine, a carbureter connected with the intake manifold thereof and having its fuel chamber communicating with the intake manifold, whereby upon operation of the engine the fuel chamber is subjected to pressure below that of atmospheric pressure, a fuel supply reservoir located below the fuel chamber of the carbureter and having 40 the fuel contained therein subjected to atmospheric pressure, a fuel conduit communicating with the interior of the fuel chamber and extending downwardly through the top of the supply reservoir into the fuel contained therein, that portion of the conduit lying between the top of the reservoir and the fuel contained therein being provided with an air intake opening and means for regulating the air intake opening.

50 3. The combination of an internal combustion engine, a carbureter connected with the intake manifold thereof and having its fuel chamber communicating with the intake manifold, whereby upon operation of the engine the fuel chamber is subjected to pressure below that of atmospheric pressure, a fuel supply reservoir located below the fuel chamber of the carbureter and having the fuel contained therein subjected to 55 atmospheric pressure, a fuel conduit communicating with the interior of the fuel chamber and extending downwardly through the top of the supply reservoir into the fuel contained therein, that portion of the conduit lying between the top of the reservoir

and the fuel contained therein being provided with an air intake opening and means operable from the outside of the supply reservoir for regulating the air intake opening.

70

4. An automatic feed system for carbureters wherein a fuel supply reservoir is located below the carbureter and in which a reduction of pressure is employed to elevate the fuel from the reservoir through a conduit to the carbureter, having a restricted air intake opening located in the conduit within the reservoir above the level of the fuel in the reservoir and below the level of the fuel elevated by the reduction of pressure in the conduit.

75

5. The combination of a carbureter, a fuel chamber therefor, means for reducing the pressure in the fuel chamber below atmospheric pressure, a supply reservoir located 85 below the fuel chamber and having the fuel contained therein subjected to atmospheric pressure, a conduit communicating with the fuel chamber and extending downwardly through the top of the reservoir into the 90 fuel contained therein, and a plurality of air intake openings placed one above the other in that portion of the conduit disposed within the supply reservoir.

80

6. The combination of a carbureter, a fuel 95 chamber therefor, means for reducing the pressure in the fuel chamber below atmospheric pressure, a supply reservoir located below the fuel chamber and having the fuel contained therein subjected to atmospheric 100 pressure, a conduit communicating with the fuel chamber and extending downwardly through the top of the reservoir into the fuel contained therein, a plurality of air intake openings placed one above the other 105 in that portion of the conduit disposed within the supply reservoir, means connecting all of the apertures with the atmosphere through a single opening, and means for regulating the passage of air through the 110 single opening.

105

7. In a liquid feed system, the combination of a liquid tank of considerable depth, a liquid reservoir above the tank, a communication between the tank and the reservoir extending to and adapted to draw liquid from said tank throughout a wide range of variation of level of the liquid therein, means to apply suction to the upper part of the reservoir, and means to restrictedly 115 admit atmosphere to said communication at vertically spaced points at least one of which is above the normal liquid level in the tank and others of which are at substantially different depths below said level.

120

8. In combination with a carbureter, a low level liquid fuel tank, a liquid fuel reservoir above the carbureter and in communication therewith to supply it with fuel, a communication between the tank and reser- 125

130

voir, means for restrictedly admitting atmosphere to said communication at spaced points one of which is above the normal liquid level in the communication and others 5 of which are below said liquid level, and means to apply to the upper part of the reservoir the same suction that is applied to the carbureter to maintain a partial vacuum in the reservoir and to draw therefrom 10 the air which enters it with the fuel.

9. The combination of a carbureter, a fuel chamber therefor, means for reducing the pressure in the fuel chamber below atmospheric pressure, a supply reservoir located below the fuel chamber and having the fuel contained therein subjected to atmospheric pressure, a conduit communicating with the fuel chamber and extending downwardly through the top of the reservoir 15 into the fuel contained therein, a plurality of vertically spaced openings in said conduit, said openings being uncovered successively as the level of the fuel in said tank drops, a tube around said conduit having a 20 closed upper end and an open bottom end, the closed end of said tube lying slightly above the level of the fuel in said reservoir and above the uppermost opening in said conduit, an opening in said tube to admit 25 atmosphere therein from the interior of said reservoir to the openings in said conduit and means operable from the outside of said reservoir for regulating the size of said opening.

30 10. The combination of a carbureter, a fuel chamber therefor, means for reducing the pressure in the fuel chamber below atmospheric pressure, a supply reservoir located below the fuel chamber and having the fuel contained therein subjected to atmospheric pressure, a conduit communicating with the fuel chamber and extending downwardly through the top of the reservoir into the fuel contained therein, a plurality of 35 openings in said conduit, said openings being uncovered successively as the level of the fuel in said tank drops, a tube around said conduit having a closed upper end and an open bottom end, the closed end of said 40 tube lying slightly above the level of the fuel in said reservoir and above the uppermost

opening in said conduit, an opening in said tube to admit atmosphere therein to the openings in said conduit, and means operable from the outside of said reservoir for regulating the size of said opening. 55

11. The combination of a carbureter, a fuel chamber therefor, means for reducing the pressure in the fuel chamber below atmospheric pressure, a supply reservoir located below the fuel chamber and having the fuel contained therein subjected to atmospheric pressure, a conduit communicating with the fuel chamber and extending downwardly through the top of the reservoir into 60 the fuel contained therein, a plurality of openings in said conduit, a tube around said conduit having a closed upper end and an open bottom end, the closed end of said tube lying slightly above the level of the fuel in said reservoir and above the uppermost opening in said conduit, an opening in said tube to admit atmosphere therein to the openings in said conduit, and means operable from the outside of said reservoir for regulating the size of said opening. 65

12. The combination of a carbureter, a fuel chamber therefor, means for reducing the pressure in the fuel chamber below atmospheric pressure, a supply reservoir located below the fuel chamber and having the fuel contained therein subjected to atmospheric pressure, a conduit communicating with the fuel chamber and extending downwardly through the top of the reservoir into 70 the fuel contained therein, a plurality of openings in said conduit, a tube around said conduit having a closed upper end and an open bottom end, the closed end of said tube lying slightly above the level of the fuel in said reservoir and above the uppermost opening in said conduit, an opening in said tube to admit atmosphere therein to the openings in said conduit, and means operable from the outside of said reservoir for regulating the size of said opening. 75

In witness whereof, I hereunto subscribe my name this 30th day of March, A. D. 1916.

CLIFFORD C. BRADBURY.
